UNITED STATES PATENT OFFICE.

ARCHIE B. McRAE, OF SANILAC COUNTY, MICHIGAN.

WAGON-BODY SUPPORT.

1,088,160.

Specification of Letters Patent.

Patented Feb. 24, 1914.

Application filed October 29, 1912. Serial No. 728,492.

To all whom it may concern:

Be it known that I, ARCHIE B. McRAE, a citizen of the United States, residing in the county of Sanilac, State of Michigan, have 5 invented certain new and useful Improvements in Wagon-Body Supports; and I do hereby declare the following to be a full, clear, and exact description of the invention, such as will enable others skilled in the art 10 to which it appertains to make and use the same.

This invention relates to improvements in wagons, and particularly to the type of dumping wagons.

15 The invention is particularly adapted to dumping wagons in which the bottom is made up of a series of longitudinally running boards or strips, which are loosely laid in the wagon and are adapted to be raised 20 to permit the load to dump directly beneath the wagon. In wagons of this class the load often is heavy enough to cause the strips which form the bottom to sag down in the middle, and it is the principal object of this 25 invention to provide a means for supporting these strips and prevent them sagging.

Another object is to provide a novel means for raising the supporting means into position.

30 Other objects and advantages will be apparent from the description and with particular reference to the accompanying drawings.

In the drawings: Figure 1 is a side elevation of the wagon body showing my invention applied, Fig. 2 is a bottom plan view, 35 Fig. 3 is a vertical transverse sectional view immediately in rear of the supporting sill, showing the sill in operative position, Fig. 4 is a similar section showing the strips in inoperative position, Fig. 5 is an enlarged side elevation of the lifting device, and Fig. 6 is a front elevation.

Referring particularly to the accompanying drawings, 40 represents a wagon box having a bottom formed of the removable strips 11.

A strap 12 is disposed vertically at one side of the wagon box, and is provided with 45 a hook 13 for engagement over the upper

edge of the side of the box, at a point midway between the ends of the box. Mounted on the lower end of the strap is a bolt 14 which passes through and supports one end of the auxiliary supporting sill 15. Disposed on the opposite side bar of the wagon body is another hook member 16, the hooked end portion 17 being engaged with the side as clearly shown. The lower end of the member 16 is provided with an outwardly 55 and upwardly extending curved portion 18 to which is pivotally connected the forked end 19 of a lever 20, this lever having a handle loop 25 on its opposite end. Disposed through the adjacent end of the sill 15 is a 60 bolt 24, this bolt having pivotally connected to its upper end above the sill, a forked link 22. This link is pivotally connected to the 65 forked portions of the lever 20.

When it is desired to raise the sill to operative position (Fig. 3), the parts being in 70 position as shown in Fig. 4, the handle 25 of the lever 20 is grasped and said lever thrown upwardly so that it engages against the strap 16. The pivot pin or pins between 75 the arms 23 and 20 are such that when the handle 25 rests against the strap 16, said pivots will lie on the inner side of the pivot 19, these pivots moving from one side to the other of the pivot 19 as the lever 20 is 80 moved up or down. Particular attention is therefore called to the construction, arrangement and operation of the lever 20 and its connected parts, by means of which a great 85 leverage is produced which permits of raising the sill into operative position even with a heavy load on, which had caused the bottom strips to sag.

What is claimed is:

An attachment for a wagon box, comprising a hook member detachably engaged over the top of one side of the box, a bolt pivotally carried by the hook member, an auxiliary sill having one end adjustably carried by the bolt, a second hook member 90 detachably engaged over the top of the other side of the wagon box, an outwardly and upwardly extending curved projection on the lower end of the second named hook member, a forked lever pivotally connected 95 100

to the terminal of said projection, a handle on the lever, a forked link having its arms straddling and pivotally connected to the arms of the forked lever, and an adjustable bolt pivotally mounted on the forked link and secured to the other end of the sill, the pivotal connection between the lever and link being arranged to swing to both sides

of the pivotal connection of the lever and projection.

In testimony whereof, I affix my signature, in the presence of two witnesses.

ARCHIE B. McRAE.
